Charles W Brown

UNITED STATES PATENT OFFICE.

CHARLES W. BROWN, OF TROY, NEW HAMPSHIRE, ASSIGNOR TO L. C. CHASE & CO., OF BOSTON, MASSACHUSETTS.

DESIGN FOR A PRINTED FABRIC.

SPECIFICATION forming part of Design No. 21,541, dated May 17, 1892.

Application filed November 27, 1891. Serial No. 413,351. Term of patent 7 years.

To all whom it may concern:

Be it known that I, CHARLES W. BROWN, of Troy, in the county of Cheshire and State of New Hampshire, have invented and produced a new and original Design for the Printing or Stamping of Horse-Blankets or other Textile Fabrics, of which the following is the specification, reference being had to the accompanying drawing, showing all the lines, stripes or bars, and squares, and the arrangement of the same necessary to fully illustrate my design.

A represents the body of the fabric.

B represents the broad partially-broken bars or stripes; C, narrower partially-broken bars or stripes.

a represents diagonal hair-lines running the length of the fabric; b, short diagonal lines running in parallel planes and at right angles to said hair-lines and making up the bars or stripes B C.

B' represents the largest uniformly-colored squares; C', the uniformly-colored parallelograms; D, the smaller uniformly-colored squares, which uniform or dense coloring is produced by the intersection of the stripes or bars, which run both latitudinally and longitudinally across the fabric.

Hitherto fabrics have been printed or stamped with a great variety of designs composed of straight lines or stripes, both continuous and interrupted, varying in width and variously grouped together, but not, so far as I know, according to my invention.

The leading feature of my design consists in the stripes or bars B C, of a peculiar composition, containing squares B' D and parallelograms C', of the color to be printed or stamped, of definite size, and short diagonal lines b, running in parallel planes, all so arranged as to show the ground or principal color of the fabric A in plats of uniform size and crossed by fine diagonal hair-lines a, except where the hair-lines are obliterated in the uniformly-colored parts B' C' D, which are too heavily colored to show the hair-lines, and grouped substantially in accordance with

the following measurements or dimensions—that is to say, the width of the bar or stripe B, running lengthwise of the fabric, is substantially one and one-eighth inches, and crosswise of the fabric one inch. The width of the bar or stripe C is substantially five-sixteenths of an inch. The squares showing the body of the fabric framed on two sides by bars B and on two sides by bars C are about one inch by one and one-eighth inches. The uniformly-colored squares B' are about one inch by one and one-eighth inches. The uniformly-colored parallelograms C', which lengthwise make up sections of C and crosswise make up sections of B, are about one and a quarter inches long and five-sixteenths of an inch wide. The smaller uniformly-colored squares D are about five-sixteenths of an inch square. Preserving substantially and proportionally these dimensions and forming or grouping these lines and bars, as aforesaid, the appearance will be presented of a succession of first broad and then narrow bars or stripes of brown or such other color as may be preferred running across the length and width of a fabric of any desired color, across the body of which will be seen, except where obliterated, the fine diagonal lines of a still different color, said broad and said narrow stripes or bars running at right angles to each other and being made up from the squares or parallelograms B', C', and D and the short diagonal lines b, thus showing the ground-color of the fabric A in squares or plats, and also showing the ground-color in spaces between the said diagonal lines b.

Of course the lines B may, if desired, be one and one-eighth inch wide crosswise and one inch wide lengthwise, if preferred.

Having fully described my design, what I claim is—

The design for a printed fabric, as herein shown and described.

CHARLES W. BROWN.
